SPRING-ACTUATED SUPPORTING DEVICE.

1,332,383.

Specification of Letters Patent.

Patented Mar. 2, 1920.

Application filed June 6, 1918. Serial No. 238,563.

To all whom it may concern:

Be it known that we, CORTLAND W. DAVIS and FRANK R. SUNDERLIN, citizens of the United States, residing at Chicago, in the 5 county of Cook and State of Illinois, have invented a new and useful Improvement in Spring - Actuated Supporting Devices, of which the following is a specification.

The invention relates to the kind of 10 spring - actuated supporting device which is commonly employed for sustaining, raising and lowering lamps and other pendent objects, and it consists, primarily, of means for preventing premature descent of an object 15 attached to such a device, even though its weight constitutes an overload for the spring. The normal load for devices of this character ranges from five to ten pounds, but by employing an added stop mechanism, 20 the fixture may be made to sustain a load up to its breaking point, as for instance, a load approximating one hundred pounds.

The device comprises a shell in which a winding drum is supported, a winding drum, 25 a coiled spring for actuating said winding drum, a pawl and ratchet locking device actuated by gravity or centrifugal force and chains attached each at one end to said drum, and at the other end to lamp or other 30 pendent object. The spring is, in such devices as heretofore constructed, of sufficient strength to counter-balance the normal load, but, in many instances, it happens that the load, being greater than the spring is able 35 to sustain, operates to unwind the spring and leave the object in a lowered position.

Our device is provided with an automatic load-sustaining stop which is inherently strong enough to carry any reasonably 40 heavy load in excess of that which the spring of the winding drum is able to resist. This load-sustaining stop, as we have shown it, consists of a pawl, the free end of which is adapted automatically to engage any one 45 of a series of somewhat closely related detents or openings (which act as ratchet teeth), unless the speed be so great that the pawl passes over it without opportunity to effectuate an interlocking engagement.

50 The addition of such an automatic stop to the ordinary suspension device in which are employed a spring-actuated drum and a clutch for locking the parts to prevent the

spring from lifting them, produces a new entity in which the lifting spring is opposed 55 by one automatic speed-controlled stop, and in which gravity is opposed by another automatic speed-controlled stop. The operator, 60 who will regulate the speed of the pendent device with his hands, may, by a quick movement, cause either stop to remain idle, or, by a slow movement effectuate the locking of the pendent device at any desired height. We propose to use clutches of any desired 65 character, the essential feature being such disposition of the clutches as will enable them to act oppositely, whereby either the spring or gravity may be effectually resisted at the will of the operator, as the 70 pendent device is raised or lowered.

Another feature of our device is the tapering form of the winding drum which is of truncated-conical shape, the object being to automatically cause the sustaining chains of 75 the device to be alternately and closely laid in a single layer upon the drum during the winding operation to thereby insure uniform winding. If the coils of the chain were superimposed, the winding speed 80 would be variable, as will be readily understood.

Several other features of the invention are the means for mounting the drum and 85 its actuating spring, the means for mounting the guide roller for the chains, the construction of the detents for the pawl, and the means for sustaining the shell or canopy of the device from and in direct contact with an over-head support. 90

The several parts of the device are so designed that all except the spring and idler pulleys may each be stamped from a single piece of sheet metal.

The details of our invention are illustrated in the accompanying drawing, which forms part of this specification. 95

Figure 1 is a view in elevation of the entire device, the shell thereof being shown in section;

Fig. 2 is a transverse vertical section, the supporting chains being omitted;

Fig. 3 is a plan view;

Figs. 4 and 5 are, respectively, views showing the cross bar of the device and elements 105 supported thereby.

A, is the shell, having diametrically dis-

posed lobes, a , extending from the upper part thereof. The bottom, a^1 , of the shell is provided with an annular groove, a^2 .

The drum, B, is of truncated conical form and is provided with a cap, C, having a conical center, c , and a cylindrical bearing, c^1 . Three integral punched tongues, c^2 , constituting tie-plates and provided with integral lugs, c^3 , extending through the bottom, c^4 , of the drum, B, unite the drum and the cap. The cap is provided with six openings, c^5 , c^6 , the former of which are the openings from which the tongues, c^2 , are punched. These several openings are adapted to receive the free ends of the pawls with which the device is provided as will hereinafter appear. The bottom of the drum is provided with a central cylindrical bearing portion, c^7 , which is disposed in alinement with the cylindrical bearing portion, c^1 .

A tube, D, constituting an axis for the drum extends from the cylindrical groove, a^2 , in the bottom of the shell, A, through the drum and to a cross-bar, E, which is mounted upon the shell, A. This tube is provided with lugs, d , extended through and riveted to the cross-bar, E. The tube is thus held securely at both its lower and its upper end, to thereby constitute a fixed axis for the drum, B. The tube, D, is made from a single sheet of metal, the meeting edges of which are united by a tongue, d^1 , and a slit, d^2 , the tongue being riveted at its outer end to prevent its withdrawal. The edges of the metal below the tongue, d^1 , are spaced apart at d^3 , for the reception of the inner end of the winding spring.

F, is the winding spring the inner end of which is folded at, f , around the proximate edge of the metal tube at the slot, d^3 . The outer end of the spring is bent around one edge of a punched tongue, c^2 , so that the tension of the spring tends to draw the bent end thereof into close engagement with said edge. The spring is thus held in operative relation to the drum, without the aid of any added securing means.

The cross-bar, E, and the shell, A, are provided with alined openings, e , a^4 , through which a headed screw, G, extends. This screw constitutes the sole supporting means for the device, which is especially desirable because it admits of a direct contact between the shell, A, and the ceiling, thereby avoiding the use of additional sustaining means, such as are commonly employed in lamp fixtures. The screw has an ornamental thumb-piece, g , by means of which it may be actuated, as well as an ornamental head, g^1 , which conceals the opening in the bottom of the shell, A.

The cross-bar, E, is provided with marginal stiffening ribs, e^1 , and, at its ends, with depending lugs, e^2 , through the threaded per-

forations, e^3 , of which retaining screws, e^4 , 65 carried by shell, A, extend.

The cross-bar, E, carries two U-shaped members, H, between which are mounted cylindrical idlers, h, for the sustaining chains of the device. These U-shaped plates 70 are cut away at, h^1 , to form guides for the chains, thus avoiding the necessity of providing the idlers, h, with grooves. The idlers are so mounted relatively to these guides as to prevent the binding of the chains as 75 they run back and forth over the idlers. The plates, H, are secured to the cross-bar, E, by integral riveted lugs, h^2 .

The cross-bar also carries an angle plate, I, which is secured thereto by riveted lugs, i . 80 The angle plate, I, carries two oppositely extending pawls, J, each of which is provided with a notch at its end, j , said pawls being loosely pivoted so as to be actuated by gravity. One of these pawls operates to prevent 85 the undue operation of the spring drum, while the other operates to prevent the pendent object from descending to a greater degree than is desired. The ends of these pawls are spaced apart a proper distance relatively to the distances between the openings, c^5 , c^6 , so that only one pawl will be in engagement at one time, through its notch, j . The pawls, as will be seen, are so shaped that 90 they ride idly over the openings of the series, when moving in one direction, and engage the walls of said openings when moving in the opposite direction. The holes are sufficiently small to allow the pawls to pass entirely over them if the winding or the unwinding of the chain is at all rapid, the engagement taking place only when the motion is slow. The operator may therefore, by 95 carefully manipulating the pendent object, bring either one of the pawls into action, 100 thus detaining the object at any desired altitude.

The sustaining means for the pendent object consists of two chains, K, both of which are secured to the small end, b , of the drum, B. These chains, as will be observed, are wound alternately upon the drum in a single layer, the ends of the chains being extended over the idlers, h, and through openings, a^5 , 115 in the shell, A. This is a superior form of winding, inasmuch as it insures the taking up of equal lengths of the supporting chains.

The general form of the shell, A, is circular, although it is provided with the lobes, a , for the reception of the U-shaped plates, H. 120

The drum, B, is provided with outwardly extending lugs, b^1 , punched from the outer wall thereof, and these lugs operate to prevent the chains from sliding off the smaller end of the drum.

All the parts of the device except the

spring and the idlers are so designed as to be fashioned by stamping from sheet metal. This is a distinct advantage, inasmuch as it eliminates the time, labor and expense incident to the casting and the machining of the parts.

The parts are furthermore secured together without the addition of extraneous securing devices, the screws, *e⁴*, being the only separate securing means with which the entire device is provided.

Having thus described our invention, what we claim and desire to secure by Letters Patent is:

15. 1. A spring - actuated suspension device including a drum, a pendent cord adapted to unwind from said drum in a single direction, and oppositely acting gravity clutches for respectively restraining the running of said cord to and from said drum.

2. A suspension device including oppositely acting gravity pawls, and detents spaced to engage only one of said pawls at the one time.

25. 3. A suspension device including oppositely acting independent pawls, and detents for said pawls spaced apart distances each unequal to the distance between the engaging parts of said pawls.

30. 4. A spring - actuated suspension device, including a speed-controlled load-sustaining stop, the movable element of said stop being supported on a fixed fulcrum.

5. A spring - actuated suspension device, 35 including a speed-controlled load-sustaining locking stop, the movable element of said stop being supported on a fixed fulcrum.

6. A spring - actuated suspension device, including an independent clutch and an independent automatic load-sustaining locking stop adapted to operate in alternation with said clutch.

7. A suspension device including oppositely acting pawls, and detents spaced 45 apart distances each less than the distance between engaging parts of said pawls.

8. A suspension device, having a truncated conical shaped winding drum, a plurality of chains attached to the small end 50 of said drum, the taper of said drum being such that the winding strain will force the coils of the chains together.

9. A suspension device, including in combination a casing, a cross bar secured to said 55 casing, a spring-actuated winding drum, and an axis for said drum supported at its respective ends by the casing and the cross bar.

10. A suspension device, including in combination a casing, a cross bar secured to said casing, a spring-actuated winding drum, and a tube constituting the axis of said drum and supported at its respective ends by the casing and the cross bar.

65. 11. A suspension device, including in com-

bination a support, a winding drum and a tubular axis therefor, said axis constituting a sleeve for an attaching screw and being fixed in said support without the aid of the attaching screw.

70

12. An extension fixture device having a support, a tube constituting an axis for a winding drum and an attaching screw extending through said tube to secure said device to the support, said tube being fixed in said support by means independent of said attaching screw.

75

13. An extension fixture device, having a casing, a chain winding drum within and sustained by said casing and an attaching screw extending through said drum to attach the device to a support.

80

14. An extension fixture device, including a spring-actuated conical chain winding drum, said drum having a cap provided with perforations adapted to be engaged by oppositely acting pawls.

85

15. A suspension device, including in combination a casing, a cross bar secured thereto, a conical winding drum, an axis and chain guides, said axis and chain guides being carried by said cross bar.

90

16. A suspension device, including a drum having a truncated conical form and a cap for said drum, said cap having a plurality of detent openings and tongues formed of metal punched from said openings and extending to and secured in a wall of the drum.

95

17. A suspension device, having a shell provided with an annular groove in the bottom thereof, a top portion, and a tubular axis resting at its lower end in said groove and secured at its upper end to said top portion.

100

18. A suspension device, including a winding drum, and a tubular axis, said axis being formed from a single piece of sheet metal the edges of which are secured together by a tongue and a slit, portions of said edges being spaced for the reception of the end of a coiled spring.

105

19. A winding drum of conical form, having at its smaller end outwardly extending lugs punched from the outer wall thereof.

110

20. A spring actuated suspension device, including in combination a drum, a cap for said drum having integral punched tongues extending to and secured to the bottom of said drum, a slotted tubular axis and a spring for said drum secured at one end in the slit of said axis and secured at the other end to one of said tongues.

115

21. A suspension device, including in combination a shell, a cross-bar secured to said shell, and a tubular axis and idler pulleys supported by said cross-bar.

120

22. A suspension device, including a shell having a cross bar, a winding drum mounted within said shell and having a series of

125

130

- detent openings in its top, oppositely disposed pawls supported by said cross bar and adapted to singly and successively engage said detent openings.
- 5 23. A spring actuated suspension device, including in combination a shell, a cross-bar supported by said shell, a winding drum within said shell, a spring for actuating said drum and oppositely disposed clutches for
10 controlling reverse movements of said drum, the several parts being formed from sheet metal and provided with suitable integral securing lugs and with openings for the reception of said securing lugs.
- 15 24. A spring actuated suspension device, including in combination a shell of circular

form having diametrically disposed lobes, a spring actuated conical winding drum within said shell, idlers in said lobes, suspension chains secured to the smaller end of 20 said drum and extending over said idlers, the idlers being so disposed that the chains, when being coiled, will slip toward the small end of said winding drum and be laid in contact with each other.

25 In testimony whereof, we hereunto set our hands this 3rd day of June, A. D. 1918.
